United States Patent Office

Des. 225,342
Patented Dec. 5, 1972

225,342

EXERCISER

Francis S. Flick, Oak Brook, Douglas A. Roberts, Elmhurst, and Edward R. Burke, Hoffman Estates, Ill., assignors to Health & Education Services Corporation

Filed Mar. 12, 1971, Ser. No. 123,917

Term of patent 14 years

Int. Cl. D21—02

U.S. Cl. D34—5

FIG.1

FIG. 1 is a top plan view of an exerciser showing our new design;

FIG. 2 is a right side elevational view, the left side being a mirror image thereof;

FIG. 3 is a bottom plan view thereof;

FIG. 4 is an end elevational view, the opposite end being a mirror image thereof.

We claim:

The ornamental design for an exerciser, as shown and described.
